UNITED STATES PATENT OFFICE

HENRY J. LANGKNECHT, OF ROCHESTER, NEW YORK, ASSIGNOR TO SHURON OPTICAL COMPANY, INC., OF GENEVA, NEW YORK, A CORPORATION OF NEW YORK

DESIGN FOR A METALLIC PATTERN STRIP FOR SPECTACLE FRAMES OR SIMILAR ARTICLES

Application filed March 30, 1932. Serial No. 43,332. Term of patent 14 years.

To all whom it may concern:

Be it known that I, HENRY J. LANGKNECHT, a citizen of the United States, residing in the city of Rochester, in the county of Monroe and State of New York, have invented a new, original, and ornamental Design for Metallic Pattern Strip for Spectacle Frames or Similar Articles, of which the following is a specification, reference being had to the accompanying drawing, forming part thereof.

Figure 1 is a side elevation of a section of a metallic pattern strip of this invention.

Figure 2 is a plan view of a section of a metallic pattern strip showing my new design, the same to be repeated for any length desired.

Figure 3 is a section taken on line 3-3, Figure 2.

I claim:

The ornamental design for a metallic pattern strip for spectacle frames or similar articles substantially as shown and described.

HENRY J. LANGKNECHT,
